REFRIGERATOR HUMIDITY CONTROL

John J. Bauman, Abington, Pa., assignor, by
mesne assignments, to Philco Corporation,
Philadelphia, Pa., a corporation of Pennsyl-
vania

Application July 10, 1945, Serial No. 604,161

8 Claims. (Cl. 62—6)

1

This invention relates primarily to refrigerating apparatus and more particularly to refrigerators of the type which include a moist-cold compartment adapted for refrigeration of foodstuffs without dehydration and wherein means is provided for maintaining, within reasonable limits, a substantially constant relative humidity within the said compartment.

In my co-pending application S. N. 565,435, filed November 28, 1944, now Patent No. 2,442,188 granted May 25, 1948, I have described a refrigerator of the above class together with means responsive to relative humidity within the compartment for removing excessive moisture from the air within the latter so as to maintain the relative humidity below a predetermined maximum. In my co-pending application S. N. 575,876, now Patent No. 2,440,628 granted April 27, 1948, I have described a device for initiating and controlling the operation of the humidity control apparatus, said device including humidity-sensitive actuating means exposed to the atmosphere of the moist-cold space and thereby operating directly in accordance with the percent relative humidity within said space.

The present invention contemplates devices for initiating and controlling the operation of the aforesaid dehumidifying means in accordance with the temperature difference between the air within the moist-cold space and the surface of the evaporator or other element which forms the active refrigerating surface for said space.

A primary object of the invention, therefore, is to provide a simplified and highly effective device for controlling the operation of dehumidifying means associated with a refrigerated moist-cold food storage compartment.

Another object of the invention is to provide a control device of the stated character which utilizes the temperature differential between the air within the moist-cold compartment and the surface of the active refrigerating element or elements exposed within the refrigerated space.

In the attached drawings:

Fig. 1 is an elevational and partial sectional view of a refrigerator embodying the invention;

Fig. 2 is a fragmentary sectional view illustrating certain details of the refrigerator construction;

Fig. 3 is an enlarged sectional view showing the

details of the control apparatus, together with the associated electrical wiring diagram, and

Fig. 4 is a view in perspective of one of the elements of the device illustrated in Fig. 3.

5 For the purposes of definition, the invention has been illustrated in the attached drawings in its application to a refrigerator of the character illustrated in my Patent No. 2,442,188 aforesaid. This comprises a cabinet 1 having an outer shell 10 2 and a metal shell or liner 3 which embraces a main food storage space 4. A machinery compartment 5 is located in the lower part of the cabinet and in this compartment is housed a motor compressor unit, designated by the reference number 6, which forms an essential part of the refrigerant circulation system by means of which the interior chambers of the cabinet are refrigerated. The cabinet further comprises a frozen food storage bin 7 having a top access opening 8 and, above the bin 7, a compartment 9 adapted to receive trays 10 in which water is frozen for manufacture of ice cubes. Above the machinery compartment and insulated therefrom is a low temperature storage compartment 11.

15 20 25 30 35 40

The three compartments 7, 9, and 11 are refrigerated through the medium of an evaporator 12 which constitutes an element of the primary refrigerant system which includes the compressor 6. Thus the compressor is connected with the condenser 13 and through the condenser and by way of a capillary tube 14 with the said evaporator 12. From the evaporator 12 a pipe 15 extends to a small primary evaporator 16 which in turn is connected through a suction pipe 17 to the compressor. The small primary evaporator 16 is operatively associated with the condensing portion 18 of a secondary refrigerant circuit which includes evaporator tubing 19 associated with the metallic inner liner 3 of the storage space 4, this secondary circuit being completed by a tube 20 which returns to the condenser 18 as illustrated.

The operation of the motor compressor 6 is controlled by a switch device 21 in the motor circuit. This switch is responsive to temperatures in the evaporator 16, and to this end the switch element is associated with a Sylphon actuator 22 which is operatively connected to a bulb 23 positioned in heat exchange relation with the evaporator 16. This control is of a character to afford a temperature differential of several degrees be-

tween the opening and closing of the said switch 21.

Means is provided for circulation of the air in the chamber 4 and for passage of this air in course of circulation in intimate heat exchange relation with a portion of the refrigerant flow tubing 17. To this end manifold chambers 24 and 25 are provided in the insulated wall of the compartment 4 and at bottom and top respectively of the latter. Louvre openings 26-26 in the liner 3 provide communication between the manifold chambers 24 and 25 and the interior of the chamber 4. At the back of the liner 3 a passage 27 is provided between the manifolds 24 and 25, this passage communicating at its lower end with the discharge side of a rotary fan or blower 28, the intake of which is connected to the manifold 24. Operation of the blower 28 has the effect of drawing air from the chamber 4 into the manifold 24 and of forcing this air upwardly through the passage 27 to the manifold 25 and through the upper louvres 26 into the upper part of the chamber 4. As illustrated in Fig. 2, the suction duct 17 extends in part longitudinally through the interior of the passage 27 and within said passage is provided with projecting metallic fins 29. Baffles 30 within the passage 27 direct the air flowing therethrough in a tortuous path in intimate thermal exchange relation with the surface of the duct 17 and the thermal transfer fins 29. Means hereinafter described is provided for controlling the operation of the blower 28 in accordance with humidity conditions within the chamber 4.

The aforescribed apparatus operates as follows: Existence of undesirably high humidity within the compartment 4 initiates operation of the blower 28 thereby causing air to be withdrawn from the chamber 4 through the manifold 24, said air being passed upwardly through the passage 27 to the manifold 25 through which it is reinjected into the chamber 4. In its flow over the surfaces of the refrigerant duct 17 and fins 29, the air loses moisture which is deposited on the said surfaces from whence the moisture eventually passes downwardly by gravity to a discharge vent 31 in the lower part of the passage 27. The operation of the blower continues until the relative humidity of the air in the compartment 4 has been reduced to a desirable value at which time the operation of the blower is automatically discontinued.

If the motor compressor 6 is functioning during operation of the blower 28, it will be evident that the suction line 17 within the passage 27 will be at a relatively low temperature, and the heat transferred from the air to the refrigerant will be absorbed in the primary refrigerating circuit.

If on the other hand the relative humidity within the compartment 4 should become excessive during an off period of the motor compressor cycle, the line 17 will be at a relatively high defrosting temperature and its capacity to absorb further heat will be relatively small. Under such conditions only small amounts of moisture could be condensed in the dehumidifying zone. Should this reduced heat exchange capacity be insufficient to restore the desired relative humidity condition within the food compartment, operation of the compressor will be re-established automatically, as follows:

As soon as the temperature of the suction line and the adjacent surfaces of the passage 27 rise substantially, heat will flow back along the suction line to the primary evaporator 16. As

pointed out above, the control bulb 23 is positioned so that it may respond to this back flow of heat thereby to re-establish operation of the compressor 6 by closing the control switch 21. This will reduce the temperature of the suction line 17 to the required extent.

This refrigerating apparatus and its mode of operation have been fully described in my aforesaid Patent No. 2,442,188 and form no part of the present invention except insofar as the elements of the apparatus relate to the control means now to be described.

In accordance with the present invention, the electrical control circuit of the actuating motor 15 for the blower 28 is provided with a control switch of the character illustrated in Fig. 3 and designated generally by the reference numeral 32. In this figure, the actuating motor for the blower 28 is indicated at 33. In accordance with 20 the invention, the switch 32 is actuated in response to a changing temperature differential between two thermo-sensitive pressure devices operatively associated with the chamber 4. Each of these devices takes the form in the present 25 instance of a Sylphon or like expandable and contractable element, 34 and 35 respectively, having connected thereto a closed bulb 36 and 37. The bulbs 36 and 37 and their associated Sylphons contain a thermo-sensitive medium which 30 expands and contracts in accordance with increasing and decreasing temperatures to which the bulbs 36 and 37 may be exposed. In the present instance the bulbs are exposed within the chamber 4 and the remaining portions of the 35 devices, together with the switch 32, are contained within the insulation between the liner 3 and the outer wall 2 of the cabinet.

As shown in Fig. 3, each of the Sylphons 34 and 35 carries at its outer end a pin 38 or other 40 suitable bearing element which respectively engage opposite sides of a lever 39 which is pivotally supported at 40 within the housing 41 of the switch device 32. Preferably and as illustrated, the points of engagement between the pins 38 and the lever 39 are slightly offset with respect to each other longitudinally of the lever, the bearing point for the Sylphon 36 being relatively remote to the pivot pin 40. The lever has an extension 42 of electrical insulating material, 50 and on the outer end of this extension is a block 43 having in the forward side thereof a notch 44, the function of which will be hereinafter described. Connected to the block 43 is a spring 45 which tends to retain the lever in a relatively 55 elevated position as illustrated. The tension of the spring 45 may be regulated from the exterior of the housing 41 through the medium of an adjusting screw 46.

Secured to the housing 41 and inside the latter is an insulator element 47 which extends upwardly at one end to form a support for a flexible switch member 48, this member being more clearly illustrated in Fig. 4. As therein shown, the member has an opening 49 through 60 which the block 43 extends and an arcuate tongue element 50, the free end of which seats within the notch 44 of the block 43, the relative dimensions being such that the tongue 50 when thus engaged with the block is held under compression. The outer end of the member 48 is provided with an electrical contact element 51 which is adapted for engagement with an opposed contact 52 which extends downwardly through a terminal extension of the insulator 47 and projects through an aperture 53 in the housing 41.

The other end of the member 48 is secured to the insulator 47 through the medium of two screws 54 which also extend to the outside of the housing 41 through the said insulator 47.

As shown in Fig. 3 when the member 48 is in the relatively depressed position with the contact element 51 in engagement with the element 52, the circuit of the motor 33 is completed with the result that the blower 28 is actuated. If, however, the lever 39 moves slightly downward from the position in which it is shown in the drawing, the terminal end of the tongue 50 which occupies the notch 44 will be moved below the plane of the member 48 whereupon the tongue, which is under compression as described, will act to elevate the outer end of the member 48 with a snap action and to thereby separate the contact 51 from the contact 52. This will open the motor circuit and will interrupt the operation of the blower. It will be noted that the extent to which the resilient member 48 may flex upwardly is limited by a stop element 55 which is carried by an insulator block 56 within the housing 41 and which may be adjusted from the outside of the housing in a manner apparent from the drawing. The contact 52 similarly limits the flexing of the member 48 in the opposite direction so that the total movement of the member between the circuit-opening and -closing positions is a relatively small one. This type of micromatic switch member is well known in the electrical arts and per se forms no part of the present invention.

The position of the lever 39 is determined by the differential between the pressures exerted by the Sylphons 34 and 35, and these pressures are functions of the temperatures of the bulbs 36 and 37 which are exposed within the chamber 4. These temperatures differ by reason of the fact that whereas the bulb 37, which communicates with the Sylphon 35, is supported in the interior of the chamber 4 in a position remote to and conductively disassociated with the surface of the liner 3, the bulb 36 is mounted in direct thermal exchange relation with the said liner. The control movement of the lever 39 is, therefore, a function of the temperature difference between the air in the space 4 and the liner 3, which in this case constitutes a functional part of the evaporator which includes the tubing 19. When this temperature difference exceeds or reaches a predetermined upper limit the motor 33 and blower 28 are actuated to circulate the air in the chamber 4 over the surface of the duct 17 and fins 29 as previously described. Since an increase in the temperature differential to or in excess of the predetermined value will generally be accompanied by an undesirable rise in the humidity of the chamber air, the device operates automatically to regulate humidity in obvious manner.

In more specific explanation of the mode of operation of the device, let it be assumed that the wall 3 (or other active refrigerating surface, as the case may be) is operating at 36° F., and that this results in maintenance of an average temperature within the chamber 4 in the neighborhood of 38° F. Under these conditions the relative humidity of the box air may go as high as 75% without danger of the air falling below its dew point temperature when in contact with the 36° wall. As long as the temperature differential between the wall 3 and the air within the chamber 4 is 2°, or less, the lever 39 will be held, by the Sylphons 34 and 35 in a position such that the switch member 48 will rest against the stop 55 remote to the contact 52. The motor 33 will then be

inoperative. Assume, further, that air at 70° enters the chamber 4 through the opened door, said air being at, say, 30% relative humidity, a common condition. Such air, if reduced to 36° F., would pass the saturation point and condensation would occur upon the wall. The introduction of this relatively warm air, however, will increase the temperature of the air within the chamber beyond the normal 2° differential, and resultant expansion of the Sylphon 35, which is subject to the air temperature within the chamber, will move the lever 39 upwardly, as viewed in Fig. 3, until the tongue 50 will have shifted to an extent causing the member 48 to snap down upon the contact 52. The motor 33 and blower 28 will thereby be actuated to circulate the air as described and will remain in operation until the 2° differential is re-established at which time the excessive humidity condition will have been rectified.

On the other hand, it will be appreciated that should the temperature of the wall fall appreciably, without a rapid corresponding decrease in the temperature of the compartment air, the Sylphon 34 will contract, thus permitting lever 39 to rise and the contacts 51—52, to close.

I claim:

1. In means for regulating humidity in an evaporator-cooled high humidity chamber, the combination with dehumidifying means, of an actuator for said means responsive to variation in the temperature differential between the said evaporator and the air within said chamber.

2. In a refrigerator comprising a moist-cold compartment and evaporator means in heat exchange relation with said compartment, the combination with means for reducing the humidity of the air within the compartment, of an actuator for said reducing means responsive to variation in the temperature differential between the said evaporator and the air within said chamber.

3. In a refrigerator comprising a moist-cold compartment and evaporator means in heat exchange relation with and presenting a surface within said compartment cooler than the compartment air and subject to undesirable moisture deposition, means for reducing the humidity of the compartment air, and actuating means for said reducing means responsive to the temperature differential between the said compartment air and the said cooling surface of the evaporator.

4. In means for regulating humidity in an evaporator-cooled high humidity chamber, the combination with dehumidifying means, of a control device operative to initiate operation of the dehumidifying means when the temperature differential between the said evaporator and the compartment air exceeds a predetermined value.

5. In a refrigerator comprising a moist-cold compartment and an evaporator associated with a wall of said compartment and operative through said wall to cool the compartment air, the combination with means for reducing the humidity of the said compartment air, of a control device for said means responsive to the temperature differential between the said air and said wall.

6. In a refrigerator comprising a moist-cold compartment having therein a cooling surface normally at a lower temperature than that of the compartment air, the combination with means for reducing the humidity of the air within the compartment, of an actuator for said reducing means responsive to variation in the temperature

7
differential between said cooling surface and the said air.

7. In means for regulating humidity in a high humidity chamber having therein a cooling surface normally at a lower temperature than that of the chamber air, the combination with dehumidifying means, of a control device operative to initiate operation of the dehumidifying means when the temperature differential between the said cooling surface and said air exceeds a predetermined value.

8. Humidity regulating means in accordance with claim 4, wherein the said control device is

8
operative also to maintain operation of the dehumidifying means until said predetermined differential has been re-established.

JOHN J. BAUMAN.
